(57) **CLAIM**

The ornamental design for an archery bow stabilizer damper housing as shown and described.

DESCRIPTION

FIG. 1 is a front-right angled view of an archery bow stabilizer damper housing, showing the new design.

FIG. 2 is a right-side view thereof.

FIG. 3 is a left-side view thereof.

FIG. 4 is a front view thereof.

FIG. 5 is a back view thereof.

FIG. 6 is a top view thereof; and,

FIG. 7 is a bottom view thereof.

The broken lines in the Figures depict environmental structure or unclaimed portions of the device and are for illustrative purposes only. The broken lines form no part of the claimed design.

1 Claim, 4 Drawing Sheets
